(57) **CLAIM**

We claim the ornamental design for a solitaire game display, as shown and described.

DESCRIPTION

FIG. 1 is a front perspective view of gaming device depicting our new design for a solitaire game display, featuring the top, front and right sides thereof;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top elevational view thereof;

FIG. 7 is a bottom elevational view thereof;

FIG. 8 is a partial front elevational view of the gaming device depicting an image provided on a first display screen according to our new design; shown broken away for ease of illustration;

FIG. 9 is a partial top elevational view of the gaming device depicting the first in a sequence of images transitionally provided on a second display screen according to our new design;

FIG. 10 depicts a second image thereof;

FIG. 11 depicts a third image thereof; and,

FIG. 12 depicts a fourth image thereof.

The broken lines shown in the drawing figures illustrate an environment of the claimed design, and form no part thereof. The subject matter in this patent or application includes images as shown in FIGS. 9-12 that transition between the figures. The process or period in which one image transitions to another image forms no part of the claimed design.
